WINFIELD S. ROGERS, OF BANTAM, CONNECTICUT, ASSIGNOR TO NELLIE SCOTT
ROGERS, OF BANTAM, CONNECTICUT.

GRINDING MACHINE.

Application filed October 15, 1924. Serial No. 743,667.

To all whom it may concern:

Be it known that I, WINFIELD S. ROGERS, a citizen of the United States, residing at Bantam, in the county of Litchfield and State of Connecticut, have invented certain new and useful Improvements in Grinding Machines, of which the following is a specification.

This invention relates to grinding machines, and more especially to that type which is operated without putting on "centers" the objects to be ground.

The principal object of said invention is to provide a grinding machine from which the cuttings and grit may be conveniently and completely washed away, ahead of the work. A second object is to provide a grinding machine to which objects may be continuously fed and their progress there-through be assisted by the action of gravity upon said objects.

To these ends, I have provided a machine comprising two horizontal grinding wheels, motive power therefor, means for adjusting the distance between said grinding wheels, a conductor for supplying water or other cooling medium to the grinding surfaces of the wheels and to the objects being ground, and a suitable support for said machine.

In the drawings, Figure 1 is a central vertical sectional view of the machine herein described, and Figure 2 is a top plan view of the same, cooling-medium conductor removed.

The numeral 1 represents a horizontal grinding wheel, 2 a horizontal feed wheel, 1' and 2' shafts, 3 a motor, 4 a frame, 6 a pipe for cooling-medium, 7 an adjusting-screw, 8 a hand-wheel for 7, 9 adjusting slide, 10 driving gear, 11 driven gear, 12 work guides, 13 clamping-screws for 12, 14 objects to be ground, 15 bearings, 16 gibs, 17 screws, 18 flanges, 19 a sprocket chain, and 20 an opening in the inclosed base.

In a grinding machine of the ordinary sort, the abrasive wheels are vertically arranged, on edge, tandem, and the cutting faces thereof are necessarily horizontal, the work of grinding being done between them, upon objects also horizontal. A great deal of trouble is often experienced with such machines, from the fact that the cuttings from the work and the grit from the wheels adhere to said wheels, causing them to wear unequally, to glaze, and to become inopera-

tive. The cuttings also get into the surface of the object being ground, injuring the same, especially if said object is of soft material. To partially offset these disadvantages, it is customary to flood the said wheels and the said work with water; and, it is so difficult to confine said water within proper bounds, that a grinding-room is usually unsanitary and disagreeable in which to work, and the moisture is more or less destructive to the machinery employed and to the material machined therein.

All such defects and objections are obviated by the use of the grinding machine herein described. In my machine, the abrasive wheels 1 and 2 are horizontally disposed on vertical arbors, so as to present vertical cutting faces, between which the object to be ground 14 is kept perpendicular. A stream of cooling medium is supplied in such manner as to constantly play upon the cutting edges of both abrasive wheels and also on the object 14.

In my device, the grinding wheel 2 is adjusted by means of the hand-wheel 8, the adjusting-screw 7 and the adjusting-slide 9, to the desired position; the object to be ground (usually a small cylinder, as 14) is fed into the space between the grinding-wheels and between the work-guides 12, 12. The motive-power may be applied to one grinding-wheel and transmitted to the other by means of a belt, chain 10, by gears or by any other means, or it may be motivated by independent means. One of said wheels is provided with a fine surface and the other with a coarse cutting surface.

In operation, one wheel is made to rotate at a comparatively low speed, while the other is rapidly revolved, the latter of which cuts the object 14 to the desired size; it being well understood that, in the operation of such machinery, the slowly revolving wheel will rotate the object being ground, while the cutting is done by the rapid wheel, whichever it may be. The object 14 is carried through the machine by its own gravity, and falls below when it has been given the desired diameter. It is also possible to feed the object 14 automatically, through a chute, from a magazine, but this method is not shown herein.

No especial claim is made for the gearing or other application of power, nor for the means of sliding the grinding-wheels into

adjustment with each other; but what I claim is:

A grinding machine comprising horizontal abrasive wheels revolving upon vertical axes and capable of grinding the surfaces of cylindrical objects fed perpendicularly therebetween, which objects automatically gravitate therethrough by their own weight; and a conduit capable of discharging by gravity

¹⁰ a cooling medium upon the vertical grind-

ing surfaces of said wheels and upon the object being ground, so as to thoroughly remove, ahead of the work, all cuttings and grit from said grinding and to maintain free from such cuttings and grit the said object and the said grinding surfaces.

In testimony whereof I have hereunto affixed my signature.

WINFIELD S. ROGERS.
